UNITED STATES PATENT OFFICE.

WILLIAM H. MINER, OF CHAZY, NEW YORK.

DRAW-BAR AND YOKE CONNECTION.

1,286,711.

Specification of Letters Patent.

Patented Dec. 3, 1918.

Application filed June 14, 1917. Serial No. 174,663.

To all whom it may concern:

Be it known that I, WILLIAM H. MINER, a citizen of the United States, residing at Chazy, in the county of Clinton and State 5 of New York, have invented a certain new and useful Improvement in Draw-Bar and Yoke Connections, of which the following is a full, clear, concise, and exact description, reference being had to the accompanying 10 drawings, forming a part of this specification.

This invention relates to improvements in draw bar and yoke connections.

One object of the invention is to provide a simple and relatively inexpensive detachable connection for standard draw bars and yoke straps of draft riggings, the connection being so arranged as to permit the reemployment of old yoke straps of the riveted 20 type without modification.

Another and more specific object of the invention is to provide a connection of the character above indicated and so designed that the parts of the connection may be made 25 in the form of forgings to thereby reduce manufacturing cost and insure a more uniform quality of material employed.

In the drawing forming a part of this specification, Figure 1 is a part longitudinal vertical section, part side elevation of a draw bar and yoke showing my improvements in connection therewith. Fig. 2 is a transverse vertical sectional view taken substantially on the line 2—2 of Fig. 1. And 35 Figs. 3 and 4 are perspective views of two elements of the connection.

In said drawing, 10 denotes the shank of a standard draw bar having a butt 11 of the usual form, said butt having upper shoulder 40 12, lower shoulder 13 and standardly spaced and located upper and lower rivet receiving holes 14 and 15. The draw bar is adapted to be detachably connected with a U-shaped wrought iron yoke strap 16 of usual form, 45 which yoke strap 16 may be either a new member or an old member of the riveted type and having upper and lower standardly spaced rivet receiving holes 17 and 18 in the front ends of the yoke arms.

50 The improved connection, as shown, comprises an upper block A, lower block B, an inverted U-shaped strap C and a transversely extending key D.

The block A is provided on its inner or 55 under side with a pair of relatively short integral cylindrical lugs 19—19, the same

being so located as to penetrate the rivet holes 17 and 14 of the upper yoke arm and a draw bar butt, respectively. The lower block B is similarly provided on its inner or 60 upper face with a pair of corresponding lugs 20—20 adapted to penetrate the rivet holes 18 and 15 of the lower arm of the yoke and draw bar butt, respectively. On its upper face, the block A is provided with a transversely extending groove or recess 21 which is designed to accommodate the upper transversely extending portion 22 of the strap or loop C to thereby provide a shouldered engagement between the strap C and the 65 block A. The lower block B is provided on its under face with a transversely extending groove or recess 23 in which is adapted to be received the key D to thus provide a shouldered engagement between said block B 70 and said key D. The depending side arms 24—24 of the strap C are provided at their lower ends with openings 25—25 to accommodate the key D and the latter, when in position, may be prevented from accidental 75 displacement by a cotter 26 or other suitable means.

The method of assembling and disassembling the parts will be obvious from the preceding description when considered in connection with the drawing, and it will be noted that the strap C and the key D, when assembled, form a band of rectangular form which encircles the blocks A and B, the draw bar butt and forward ends of the yoke 80 16. As will be obvious, the blocks A and B, the strap C and key D may all be made in the form of forgings, the blocks A and B being preferably drop forged. In this manner, the parts may be made at relatively 85 small expense while at the same time insuring material of a high quality and free from latent defects.

It will also be seen that the length of the arms 24—24 of the strap C may be varied, 90 or the location of the holes 25—25 therein may be varied, to thereby accommodate the connection for draw bar butts of different heights and without changing the character or size of the blocks A and B. It is also 95 possible with my construction to have the openings 25 of such height as to accommodate keys D of different thicknesses to accomplish the same results, that is, to provide connections for different size draw bars. 100 105

Although I have herein shown and described what I now consider the preferred

embodiment of my invention, the same is merely illustrative, and I contemplate such changes and modifications as come within the scope of the claims appended hereto.

5. I claim:

1. In means for detachably connecting a draw bar and yoke having standardly located rivet receiving holes, the combination with independent upper and lower blocks, each having a pair of lugs adapted to penetrate the respective upper and lower sets of rivet holes in the yoke and draw bar, of a detachably united two-piece rectangular band arranged to engage said blocks and surround the latter, the draw bar butt and yoke ends to thereby hold said blocks in position.
10. In means for detachably connecting a draw bar and yoke having standardly located rivet receiving holes, the combination with independent upper and lower blocks, each having a pair of lugs adapted to penetrate respectively the upper and lower sets of rivet holes in the yoke and draw bar, of a band arranged to surround the draw bar butt, the ends of the yoke arms and said blocks, said band comprising a U-shaped loop and a cross key detachably associated therewith, the key being located outside of the draw bar.
15. In means for detachably connecting a draw bar and yoke having standardly located rivet receiving holes, the combination with independent upper and lower blocks, each having a pair of lugs adapted to penetrate a
20. In means for detachably connecting a draw bar and yoke having standardly located rivet receiving holes, the combination with independent upper and lower blocks, each having a pair of lugs adapted to penetrate respectively the upper and lower sets of rivet holes in the yoke and draw bar, of a
25. In means for detachably connecting a draw bar and yoke having standardly located rivet receiving holes, the combination with independent upper and lower blocks, each having a pair of lugs adapted to penetrate respectively the upper and lower sets of rivet holes in the yoke and draw bar, of a
30. In means for detachably connecting a draw bar and yoke having standardly located rivet receiving holes, the combination

with independent upper and lower blocks, each having a pair of lugs adapted to penetrate the respective upper and lower sets of rivet holes in the yoke and draw bar, of a detachably united two-piece rectangular band arranged to engage said blocks and surround the draw bar butt and yoke ends to thereby hold said blocks in position, each piece of said band having shouldered engagement with one of said blocks.

4. In means for detachably connecting a draw bar and yoke having standardly located rivet receiving holes, the combination with independent upper and lower blocks, each having a pair of lugs adapted to penetrate respectively the upper and lower sets of rivet holes in the yoke and draw bar, of a U-shaped loop adapted to straddle said blocks, the draw bar butt and the ends of the yoke arms, and a transversely extending key detachably associated with said strap and disposed outside of the draw bar, said blocks having transversely extending grooves in their outer faces adapted to accommodate the transversely extending portion of the U-shaped strap and said key to thereby obtain a shouldered connection between said band and both of the blocks.

In witness that I claim the foregoing I have hereunto subscribed my name this 12th day of June, 1917.

WILLIAM H. MINER.
